UNITED STATES PATENT OFFICE.

KARL AHMELS, OF CASSEL, GERMANY.

DOUBLE TELESCOPE.

1,412,442.

Specification of Letters Patent. Patented Apr. 11, 1922.

Application filed May 10, 1920. Serial No. 380,397.

To all whom it may concern:

Be it known that I, KARL AHMELS, a citizen of the German Republic, residing at Cassel, German Republic, have invented certain new and useful Improvements in Double Telescopes, of which the following is a specification.

With the double telescopes of known construction the adjustment of the lens as regards eye-distance and distinctness of the image is effected through the bending of joints, by means of toothed wheels and pinions or, otherwise expressed, through elements which are difficult to make and expensive. This invention relates to an adjusting device which consists only of parts which move in slits and of cylindrical parts which turn the one in the other. In this manner the advantage is obtained that the connection between the two telescopes is rectilinear and shiftable only in itself, the optical axial distance of the tubes being regulated through turning a member of the corresponding tube or telescope, the axis of the lens tube being eccentrically arranged in said member.

In the accompanying drawing the invention is shown by way of example:

Fig. 1 is a perspective view of the double telescope.

Fig. 2, shows in a similar view as Fig. 1, the different parts of the telescope separated from each other.

The casings 1 and 2 are rigidly connected by a transverse piece 3. The casings 1 and 2 form, so to say, eccentric rings for the reason that the lens tubes 4 are in fact eccentric owing to a thickening 8 arranged at one side of the lens tube. Thus, the socket 5 for the 40 ocular lens 6 and the socket 7 for the objective are eccentric the one with regard to the other and move towards or away from one another if one of the sockets 5 or both sockets 5 are rotated. The lens sockets 5 are connected with one another by a bridge 9. The sockets 5 are milled. If one of the sockets 5 is rotated, the corresponding ring 4 is displaced in its casing 1 or 2 through the joining piece 8 so that the optical axis 10 moves towards or away from the optical axis 11 and vice versa.

The transverse piece 3 which rigidly connects the tubular casings 1 and 2 is composed of the fixed part 12 and of the removable part 13. This removable part 13 is fixed upon the part 12 by means of screws 14. The fixed part 12 has at its middle a vertical guide slot 16 designed to receive a slide 15. The removable part 13 has in its inner wall a rectangular horizontal cavity 17 and further a horizontal slot 18 for the passage of the thickened part 19 of a screw 21 mounted in a horizontal plate 20. The inner end 22 of screw 21 engages with a slanting slot 23 of the vertical slide 15. The horizontal plate 20 serves on the one hand to guide the screw 21 and on the other hand to cover the slot 18. The screw 21 has a milled head 24.

If the screw 21 is moved to the right or left, it moves the plate 20 in the corresponding direction, the vertical slide 15 being lifted or lowered according to the direction in which the head 24 of the screw 21 is being moved.

The usefulness of the telescope is still further increased by a mirror 31 through which persons or objects at the back of the person who uses the telescope can be observed. Instead of a plane mirror, as shown, a convex mirror or the like can be used in order to enlarge the range of observation.

A hand 33 of the head 24 of the screw 21 moves over a scale 32 designed to indicate a special adjustment.

I claim:—

1. Improved means for adjusting telescopes comprising in combination the tubular casings rigidly connected the one with the other, a lens tube in each tubular casing, a thickening at one side of said lens tube rendering the opening through said tube eccentric, an adjustable bridge connecting the lens tubes, and means for uniformly moving the said lens tubes towards or away from one another.

2. Improved means for adjusting telescopes comprising in combination the tubular casings, a lens tube in each casing, a thickening at one side of the opening through said lens tube rendering said tube eccentric in its casing, a transverse piece rigidly connecting said casings and having a vertical guide groove at the middle, a plate removably fixed upon the front side of said transverse piece having a longitudinal slot and a longitudinal rectangular cavity in its inner wall, a vertical slide fixed at the upper end to said bridge of the lens tubes guided in

said vertical groove of the transverse piece and having a slanting slot near its foot end, a regulating screw with milled head in said longitudinal slot of the removable plate 5 engaging with its inner end with said slanting slot of the vertical slide, and a plate upon the stem of said screw located in said rectangular cavity of the removable plate, sub-

stantially as described and shown and for the purpose set forth.

In testimony whereof I affix my signature in presence of two witnesses.

KARL AHMELS.
